Fred E. Parker.

Inventor,

Martin V. B. Etheridge
By his Attorney *John C. Parker,*

UNITED STATES PATENT OFFICE.

MARTIN V. B. ETHRIDGE, OF BOSTON, MASSACHUSETTS, ASSIGNOR OF TWO-THIRDS TO JOHN SWANN, OF NEW YORK, N. Y., AND HENRY E. WAITE, OF WEST NEWTON, MASSACHUSETTS.

TIME-PIECE DIAL.

SPECIFICATION forming part of Letters Patent No. 401,697, dated April 16, 1889.

Application filed June 20, 1888. Serial No. 277,634. (No model.)

To all whom it may concern:

Be it known that I, MARTIN V. B. ETHRIDGE, a citizen of the United States, residing at Boston, in the county of Suffolk and State of Massachusetts, have invented certain new and useful Improvements in Time-Piece Dials; and I do hereby declare the following to be a full, clear, and exact description of the invention, such as will enable others skilled in the art to which it appertains to make and use the same.

This invention refers to a time-piece dial, and relates especially to that class of time-piece dials wherein the hours of the day, from one to twenty-four, are designated by means of a radial series of intermittently-rotary spindles, each carrying a block, plate, or disk, on the faces of which are marked numerals representing the hours; and the present improvement consists, essentially, in novel means for imparting a partial rotation to each spindle of the series consecutively during the revolution of the clock-hands and for steadily holding said spindles in the position to which they may have been turned. In addition to these essential features of the improvement this invention includes certain details in the construction, arrangement, and combination of the various parts, substantially as will be hereinafter fully described and claimed.

In the annexed drawings, illustrating my invention, Figure 1 is a rear view of a time-piece having a dial of the class above referred to and showing my invention applied thereto, the rear portion of the time-piece being removed to expose the shifting spindles within, as also their actuating mechanism. Fig. 2 is an enlarged detail perspective view of a portion of the same, showing a couple of spindles and the disk on the hour-hand sleeve. Fig. 3 is a view showing a disk and a portion of a couple of the spindles, the notch in the disk being closed and the projecting device removed, so that the time-piece may be converted into an ordinary time-piece. Fig. 4 is an edge view in partial section showing a modification in the construction of the revolving disk or plate which operates to turn the spindles. Fig. 5 shows an elevation and a

horizontal edge view of the same and indicates the manner in which it operates.

Similar letters of reference designate corresponding parts throughout all the different figures.

As I have already stated above, the dial to which my present invention is applicable is of the kind having a radial series of rotary spindles, which are provided with numeral blocks, plates, or disks, upon which the hours of the day from one to twenty-four are marked. These spindles are suitably journaled at each end, so as to be rotated under the impulse of actuating devices arranged in connection therewith. They are thus caused to present at one time one face to view and at another time another face, so that the numeral indicated on the front face of the blocks is subject to constant change in order that the entire time-piece may accomplish the object of its construction, which is to note the time of day throughout the whole of the twenty-four hours by a regularly-increasing series of hour-marks from one to twenty-four.

The purpose of the present improvement is to provide improved means for individually rotating the spindles and for holding them immovably in the position to which they may have been moved.

A denotes the spindles, which are arranged in a radial series, as shown, their inner ends being journaled in a suitable rim or sleeve, *a*, while their outer ends are carried in bearings formed in the clock-casing. Each spindle *A* carries at or near its outer end a plate, disk, block, or other device, *B*, that registers with one of the slots *b* in the outer dial-plate when said outer dial-plate is employed. (See Fig. 2.) These blocks *B* are preferably rectangular in form, although it is obvious that they may be made in any convenient way. The spindles *A* also carry at some convenient point thereon—as, for instance, at or near the center—a small quadrangular block or bearing, *C*, from each face of which projects a shoulder or pin, *c*. It will be evident, therefore, that if a suitable actuating device comes in contact with the projecting pins *c* the spindles will be successively rotated, so that the blocks *B* will be

caused to shift their faces, and if the device which acts upon said projecting pins moves properly with relation to the movements of the hour-hand this changing of the faces of the numeral-blocks will be such as to display in succession on the several numeral-blocks the proper symbols for designating the hours correctly when the hour-hand again passes around.

10 I will now describe the agency which acts upon these pins to rotate the numeral-blocks.

Upon the hour-hand sleeve (see Fig. 2) is firmly secured a circular block, plate, disk, or other device, D, so as to revolve with said sleeve. This plate or disk may be of greater or less diameter, if desired. It will, however, be so constructed as to permit its circumference to project over the quadrangular blocks C. This plate D is formed at one point in its circumference with a notch, recess, indentation, aperture, or shoulder, d, preferably rectangular in shape, to correspond somewhat to the form of the block C, which in the present example of my invention is quadrangular in shape.

25 Variations in the size and shape of the notch d may doubtless be employed to a considerable extent, as also obvious differences may exist in the structure of the blocks C, 30 the idea employed in this invention being that the plate D shall be furnished with such a notch that when said plate in its revolutions brings the notch opposite the turnstile-block the outline of the notch will surround 35 the block, so that the latter may be free to turn without coming in contact with the plate, for it may be mentioned that the plate D is in proximity to the block C. Thus it will be observed that the blocks C rest with their 40 faces close to the plate D, and will be held firmly and cannot rotate or become displaced, except at such times when the notch d comes opposite one of these blocks. Then said block may turn if an agency acts thereupon. A 45 rod or arm, E, projects from the disk or plate D in the notch d, and preferably on a radial line of the disk. It extends beyond the periphery of the disk, so that as said disk revolves said pin or arm E will strike the projecting pins c c, which lie in its path.

50 The operation of turning the spindles by means of the projecting pin or arm E and of holding them by the disk D firmly in the positions to which they may have been turned 55 will be evident from the description of the construction and relation of the parts that have just been given without need of further detail. The plate D will hold all the spindles firmly in place and keep them from rotating, 60 except at the times when the notch is brought opposite any one block, which block is thus set free, and the pin E is permitted to come into contact with the pin c on the quadrangular block and thus rotate the spindle.

65 In Figs. 4 and 5 I have represented a modification in the construction of the disk D. The essential principle of operation still ob-

tains and is the same as that employed in the other figures; but the construction of the parts is different. In Figs. 1 and 2 we have a simple flat circular plate notched at one point in its periphery and carrying a projecting pin, which pin is in a radial line of the disk. In Figs. 4 and 5 we have a circular plate, D', which is intact and is secured 70 upon the hour-hand sleeve in like manner with the disk D. The disk or plate D' is provided with a peripheral flange, F, which projects toward the series of spindles and is at right angles to the disk D'. Said flange is at 80 a certain point notched or recessed at f. (See Fig. 5.) Instead of having the plate or disk in close proximity to the series of quadrangular blocks on the turnstiles, I have in this modification the edge of the flange F located 85 in proximity to said blocks. Projecting horizontally from the disk D' at a point near the notch f in the flange is a suitably-shaped pin or other outwardly-extending device, (denoted G,) which is so located that during the revolution of the disk it may come in contact with the pins c on the blocks C. The position of the pin with respect to the slot f is shown in Fig. 5, where it is seen to be opposite the central line of said slot.

95 With this modified construction the operation of the invention is substantially the same as already described. The flange F will hold all the spindles firmly in place and keep them from rotating, except at the times when the notch f is brought opposite any one block, which block is thus set free, so that the pin or extension G is permitted to act on the pin c and thus rotate the spindle. This modified arrangement of the disk and its attachments 100 serves merely to indicate another way of carrying out the essential idea of the present invention, which is that of a notched or indented revoluble disk on the hour-hand sleeve, which disk has a projecting pin that 105 successively engages turnstiles carried by the spindles, and thus causes said spindles to be rotated, so that the hours of the day from one to twenty-four may be displayed on the face 110 of the dial.

115 In Fig. 3 the disk D is shown similar to that in Fig. 2; but instead of having the notch or indentation d said notch has been closed or filled up, so that the disk is intact and a complete disk. Furthermore, the projecting pin or arm has been removed. Obviously the spindles cannot now be rotated. Thus the time-piece or clock is converted into an ordinary clock, and although the spindles remain, yet they designate the hours from one to 120 twelve only, and all the other mechanism of the time-piece may be that of the twelve-hour system.

125 With my present improvement all friction is avoided when the numeral-blocks are turned, excepting the simple touch of the arm that projects from the disk when said arm passes by each turnstile, which touch is very slight. Only one block can turn at once, and

then only at its proper time. When the revolving disk or locking-plate carries the projecting arm or pin through each turnstile, it supplements the action of the arm or pin by preventing the turnstile from returning to its original position, when the pin elevates it and acts as a locking-plate for all the turnstiles by keeping their faces level with the clock-plate. Thus when the clock is shipped from the factory no jarring can ever get the blocks out of place.

Having thus described my invention, what I claim as new, and desire to secure by Letters Patent, is—

- 15 1. In a time-piece dial, a series of radial rotary spindles carrying turnstiles, in combination with a single-notched disk or plate and a projecting pin or arm thereon, substantially as described.
- 20 2. In a time-piece dial, the combination of a series of radial rotary spindles having turnstiles thereon, a disk secured to the hour-hand sleeve and having a single notch in its periphery, and a projecting arm or pin upon the disk, substantially as described.
- 25

3. In combination with one or more radial spindles of a time-piece dial, said spindles being provided with projecting pins thereon, a notched disk and a pin or arm projecting from said disk, substantially as described. 30

4. In a time-piece dial, the combination of a series of radial rotary spindles carrying turnstiles, a disk secured to the hour-hand sleeve having a notched flange, and a projecting pin or arm on the disk, substantially as 35 described.

5. In a time-piece dial, the combination, with a series of radial rotary spindles carrying turnstiles, of the disk D, notched at d, and the pin or arm E, projecting from the disk, 40 substantially as described.

In testimony whereof I affix my signature in presence of two witnesses.

MARTIN V. B. ETIIRIDGE.
